EXPANSION PROVIDING ROOF STRUCTURE

Herbert Alfred Faber, Cincinnati, Ohio

Application July 14, 1937, Serial No. 153,465

10 Claims. (Cl. 108—33)

This invention relates to roof structures.

In particular, the invention relates to improvements in means for securing preferably metallic membrane surfacing material to a sub-structure, a novel provision being made to secure the surfacing material in a manner allowing for changes in dimension thereof due to expansion or contraction.

The invention contemplates the use of relatively thin sheets of copper for the surfacing material, this material being commercially obtainable in long sheets of moderate width, and substantially non-corrosive under normal atmospheric conditions. To provide for the accentuated dimensional changes of the sheeting, unavoidable in copper because of its relatively high coefficient of expansion,—said exaggerated expansion and contraction being a factor which has hitherto deterred its general use as a roof surfacing material—the copper sheet is not rigidly secured, as by nailing or cementing, to the roof structure itself. For securing the surfacing material, resilient means are employed, preferably comprising coil springs of bronze or other non-corrodible material, stationed at spaced locations along the margins of the copper sheets, and secured to suitable rigid anchors, which may be spaced from the roof structure itself, but coextensive with the sides thereof.

Advantageously, the customary rain gutters may be employed as the anchors, it being understood that suitable spaced bracers or stiffeners may be provided to strengthen the gutter structure against the pull of the aforementioned springs.

In accordance with this invention, the metal sheets may be laid over the roofing structure, which in modern house construction may include a suitable flat concrete slab overlaid with a bed of cinder concrete, gypsum sawdust mixture, or other similar material. The said material is preferably screeded to provide a peak or arch, and may preferably have shallow, broad corrugations. The copper sheet is caused to follow the contour of the corrugations, and may be provided with an undercoating of asphaltic cement, not for the purpose of structurally securing the surfacing material, or for rendering the roof structure water-tight, but to cushion the copper sheeting and prevent or dampen vibrations which may be induced in the copper of the roof surface by the play of wind thereon.

Preferably, the roof surface may be spanned by rods or strips of copper or bronze, preferably lying in the valleys of the corrugated roof sur-

face, and secured to the anchoring springs at each side of the roof. The rods serve to prevent buckling of the surfacing material when the latter is expanding in a direction perpendicular thereto, but do not deter the normal expansion or contraction of the copper. It is intended that the roof spanning rods be of a material having a coefficient of expansion substantially equal to that of the surfacing material.

Characteristics of the invention, therefore, are the elastic quality of the surface-material holding means, and the uniformity of contact of the surface-material with the roof structure.

In the accompanying drawing:—

Figure 1 is a vertical section of a roof structure;

Figure 2 is an enlarged sectional view of the structure near one rain gutter, showing a tensile-spring anchor and gutter stiffening brace;

Figure 3 is a transverse section taken along 3—3 of Figure 2, illustrating the corrugations of the roof surface, with the transverse roof-spanning rods lying in the valleys of the corrugations; and

Figure 4 is a fragmentary plan view of the roof structure illustrating the sub-structure, the spaced resilient anchors, and the connection of the spanning rods therewith.

Referring to Figure 1, 10 designates generally a flat slab concrete roof sub-structure, provided with suitable metallic rain gutters 11, 12 firmly secured to the concrete slab 15 of the roof structure at the sides thereof, and coextensive with the sides. Building walls are indicated at 13, 14. The flat slab 15 is preferably overlaid with a bed 16 of cinder concrete, gypsum sawdust mixture, or other material which can be bonded to the concrete sub-base, and worked, as by screeding, into a low peaked or arched configuration as indicated in Figure 1, to provide a water shedding structure. It is preferable also that in screeding the bed 16, it be given a shallowly corrugated form, the said corrugations extending transversely of the roof as indicated in Figures 3 and 4.

Advantageously, the roof surfacing material 17 may be copper sheeting or foil, too thin to be used alone, but adequate to provide a weather-tight, durable roof when laid on, and secured to, the supporting sub-structure in the manner herein described. The roof surface is preferably coextensive with the said structure, and may be assembled of moderately wide sheeting, suitably rendered water-tight by overlapping joints and soldering where necessary. As illustrated in Figure 3, the sheeting is caused to follow the corru-

gations of the bed 16; and as shown in Figure 4, may be laid on a cushioning coating 18 of non-resonant adhesive material, such as asphalt, to prevent or dampen wind-induced vibrations. The 5 sheeting 17 preferably overlies the gutters, see Figs. 2 and 4, and is provided at such overlying edges with reinforcement 19, thus affording strong marginal surfaces 19a. It is a feature of this invention that the sheeting is not rigidly 10 secured to the roof structure at any point.

To hold the sheeting 17 in contact with the roof structure, and yet permit movement thereof relative to the structure to allow for expansion and contraction of the copper in any direction and 15 in any degree, resilient anchoring means, preferably in the form of bronze springs 21, are preferably hooked through the margins 19a at spaced stations in registry with the valleys of the roof corrugations; said springs being swivelly secured 20 by hooking their outer ends to a wall of each rain gutter 11, 12. It will be understood that the spring anchors at each side of the roof are in mutual registry, to insure an even, unbiased, tensile pull on the surfacing material. To stiffen 25 the gutters 11, 12 against the pull of the springs, compression members 22 may be provided as indicated in Figures 2 and 4.

Preferably, additional securing means are provided, in the form of roof-spanning rods 23 having 30 eyelets 23a through which mutually registering springs 21 may be hooked at each side of the roof. It is obviously preferable that the rods 23 be of a material having a coefficient of expansion equal to that of the roof surfacing material.

35 As previously stated, the cinder-concrete bed 16 is preferably convex or peaked. As indicated in Fig. 2, the arrangement of the springs 21 with respect to the gutters 11, 12 and the roof structure 10 brings the longitudinal axes of the springs 40 into conformity with the slope of the roof structure, thus exerting a tensile pull in the plane of the oppositely sloping sides of the roof, if peaked; or substantially tangential to the curvature thereof, if arcuate as shown in Fig. 1. The tendency 45 of the springs, and likewise of the rods 23, to "flatten" the contour of the roof serves to maintain the sheeting 17 in evenly tensioned contact with the bed 16 over the entire surface thereof.

50 The springs 21 should be sufficiently resilient to expand readily, as contraction of the metal shortens the overall span thereof, without imposing an undue strain on the margins 19a of the sheeting, or on the rods 23. The springs also 55 should be sufficiently expanded under any given temperature condition to be contractile under conditions of increasing temperature and consequent expansion of the sheeting 17. It is fundamental that at all times, sufficient tension be 60 exerted on the sheeting to urge it into close engagement with the bed 16.

It will be seen, that pursuant to this construction, expansion and contraction of the copper surfacing material in any direction and in any 65 degree are provided for in a manner which does not impose a strain on the roof sub-structure, and which precludes tearing or otherwise rupturing the surfacing material. The springs 21 yield to the movement of the copper under its expansion or contraction, and thus, with the rods 23, maintain the surfacing material in intimate contact with the underlying bed 16. Expansion or contraction in a direction longitudinally of the roof, that is, at right angles to the corrugations 70 of the roof structure, is accommodated by the cor-

rugations per se; and buckling of the surfacing material by its expansion in this direction is effectively resisted by the spring-induced downward pressure of the rods.

Whereas I have described my invention by 5 reference to specific forms thereof, it will be understood that many changes and modifications may be made without departing from the spirit of the invention.

I claim:

1. A roof structure, including, in combination, a structural base, a weather-exposed unitary metallic sheet overlying said base and coextensive therewith, and resilient means arranged to urge the said sheet into contact with said structural 15 base.

2. A roof structure, including, in combination, a structural base, anchoring means associated therewith, a weather-exposed unitary metallic sheet overlying said base and coextensive therewith, and resilient means having extremities respectively secured to opposed marginal edges of the said sheet and to said anchoring means, for urging the said sheet into contact with said base, 20

25 3. A roof structure, including in combination, a structural base, a weather-exposed metallic sheet overlying said base and coextensive therewith, anchoring means spaced from the said base, and resilient means having extremities respectively secured to the marginal edges of said sheet 30 and to the said anchoring means, said resilient means exerting a tensile pull on the said sheet and thereby urging it into contact with the said base.

4. A roof structure, including, in combination, 35 a structural base, a weather-exposed metallic sheet overlying said base and coextensive therewith, water gutters coextensive with the sides of said base and secured thereto, and tensile springs having ends respectively secured to the marginal 40 edges of the said sheet and to the said gutters, said resilient means exerting a tensile pull on said sheet and thereby urging it into contact with said base.

5. A roof structure, including, in combination, 45 a structural base, a weather-exposed metallic sheet overlying said base and coextensive therewith, anchoring means coextensive with opposite sides of said base and spaced therefrom, and paired, tensile springs secured to the marginal 50 surface of said sheet and to said anchoring means and arranged to exert a downward pull on said sheet, said tensile springs being at spaced stations at each of the opposite sides of the said base, each of said springs being in registry with a similarly 55 acting spring on the opposite side, said springs thus exerting a localized, transverse tensile pull on the metal sheet, whereby the said sheet may be resiliently held on said base.

6. A roof structure, including, in combination, 60 a structural base, weather-exposed surfacing material overlying said base, anchoring means coextensive with opposite sides of said base, said anchoring means additionally serving as water conductors for the said roof, and means for resiliently holding said surfacing material into contact with said structural base, including tensile springs secured to the marginal edges of the said surfacing material and to the anchoring means and paired with springs disposed on the opposite side of said roof structure, and transverse tension members spanning said surfacing material and in contact therewith, said members secured at their terminal ends to the said springs. 70

7. A roof structure, including, in combination, 75

- a structural base, weather-exposed surfacing material overlying said base, anchoring means co-extensive with opposite sides of said base, said anchoring means additionally serving as rain-
5 water conductors for the said roof, and means for holding said surfacing material in contact with said structural base while permitting movement relatively thereto, including tensile springs secured to the marginal edges of the said sur-
10 facing material and to the anchoring means and paired with springs disposed on the opposite side of said roof structure, and rods secured at their terminal ends to said springs and transversely spanning said roof structure in contact therewith, said rods having a coefficient of expansion substantially equivalent to said surfacing material.
15 8. Means for securing a membrane weather-proofing material in slidable contact with a relatively flat structural surface, including springs anchored to said structural surface and to said weatherproofing material along marginal portions thereof, said springs arranged to exert a downwardly directed tensile pull on said weather-proofing material and thereby urging it into contact with said structural surface.
20 9. Means for resiliently holding a membrane roofing material in contact with a structural surface, said roofing material having a relatively great coefficient of expansion, including springs having their ends respectively swivelly anchored
25

and secured to said roofing material along oppositely located marginal portions thereof, and rods spanning said roofing material and lying in contact therewith, said rods joined at their terminal ends to the said springs, whereby expansion and contraction of the said roofing material is absorbed by the flexing of the said springs, said roofing material being held thereby under uniform tension.
30

10. Means for holding a membrane roof surfacing material in contact with a structural surface against the movement of said material induced by expansion and contraction thereof, including, in combination, springs having one end swivelly anchored and another end secured to said roofing material, said springs being located on oppositely disposed side-surfaces thereof, said springs exerting a downwardly directed tensile pull at the opposite sides of said material, and transverse rods spanning said roofing material in contact therewith and secured to said oppositely disposed springs, whereby movement of the said material in the line of action of said springs is taken up by the flexing thereof, and the expansion or contraction of the surfacing material in a direction perpendicular to said line of spring action is substantially unopposed by said springs or by said transverse rods, the said rods serving to prevent buckling or otherwise separation of the said surfacing material from the said surface.
